UNITED STATES PATENT OFFICE.

WILLIAM F. MANGELS, OF CONEY ISLAND, NEW YORK, ASSIGNOR OF ONE-HALF TO WILLIAM S. SMITH, OF SAME PLACE.

MERRY-GO-ROUND.

SPECIFICATION forming part of Letters Patent No. 669,842, dated March 12, 1901.

Application filed June 6, 1900. Serial No. 19,246. (No model.)

To all whom it may concern:

Be it known that I, WILLIAM F. MANGELS, a citizen of the United States, and a resident of the city of New York, (Coney Island, borough of Brooklyn,) in the county of Kings and

5 State of New York, have invented a new and Improved Merry-Go-Round, of which the following is a full, clear, and exact description.

The invention relates to merry-go-rounds 10 having crank-shafts for imparting movement to the seats; and the object of the invention is to provide certain new and useful improvements in the construction of merry-go-rounds, whereby the driving-gear for the crank-shafts 15 is completely relieved of the weight of the revoluble frame, and consequently undue strain is avoided and the frame is supported independently of the gearing to insure an easy running of the machine with comparatively 20 little power.

The invention consists of novel features and parts and combinations of the same, as will be fully described hereinafter, and then pointed out in the claim.

25 A practical embodiment of the invention is represented in the accompanying drawings, forming a part of this specification, in which similar characters of reference indicate corresponding parts in all the views.

30 Figure 1 is a plan view of the improvement with the seats and other ordinary parts of the merry-go-round omitted. Fig. 2 is an enlarged plan view of the central portion of the device shown in Fig. 1 and with part of the 35 fixed gear broken out, and Fig. 3 is a sectional side elevation of the same on the line 3-3 in Fig. 2.

The improved merry-go-round is provided with a suitable central post A, on which is 40 fastened a support B, having an annular ball-bearing C for engagement with the under side of a frame D, mounted to turn loosely on said post as a center, said frame D being formed of suitable radially-extending beams 45 preferably made in sections fastened together, the inner sections of the beams being connected with each other by suitable rings, as is plainly indicated in Fig. 1, the outer sections being connected with each other by con-

necting beams or braces, also fully shown in 50 Fig. 1. The frame D is provided with the usual pin or lantern wheel E, connected with the power for rotating the frame in the usual manner.

On the revoluble frame D are journaled 55 crank-shafts F, having the usual cranks F' at or near their outer ends for connection with horses or other seats mounted to rock on said frame and receiving a rocking motion from the crank-arms during the time the 60 frame D is turned around. The crank-shafts F are arranged in pairs, and each pair is provided with gear-wheels G in mesh with opposite sides of a gear-wheel G', secured on a shaft G², journaled on the frame D between 65 the shafts F of a pair of shafts, as will be readily understood by reference to Figs. 1 and 2. On the inner end of each shaft G² is secured a pinion G³ in mesh with a bevel gear-wheel G⁴, secured to the center post A above 70 the frame D, as is plainly illustrated in Fig. 2. Now it is evident that as the several pinions G³ are in mesh with the fixed gear-wheel G⁴ a rotary motion is simultaneously given to all the shafts G² when the frame D is turned, 75 and the rotary motion given to each shaft G² is transmitted by its gear-wheel G' to the gear-wheels G on a pair of crank-shafts F, and consequently the desired rocking motion is given to the horses or other seats during 80 the time the frame D is revolved.

By having the bearing for the frame D completely independent of the gearing for driving the crank-shafts F it is evident that said gearing is completely relieved of all strain 85 incident to the weight of the frame, and consequently it requires comparatively little power to rotate the frame D by the motor used for the purpose. Furthermore, all danger of the gear-wheels binding is completely 90 avoided whether the frame is loaded to a greater or less extent.

It is understood that the pairs of gear-wheels G in mesh with opposite sides of the gear-wheels G' form, with the latter and the 95 pinion G³, a train of gear-wheels for rotating the crank-shafts from the fixed gear-wheel G⁴ when the frame D is rotated.

Having thus fully described my invention, I claim as new and desire to secure by Letters Patent—

5 A merry-go-round, comprising a central post, an annular bearing secured to said post, a frame mounted to turn on said bearing, a gear-wheel fixed to the post above the frame, crank-shafts arranged in pairs on the frame, a pinion-shaft arranged between each two of 10 a pair of shafts and having driving connec-

tion therewith, and a pinion on each pinion-shaft meshing with said gear-wheel, substantially as specified.

In testimony whereof I have signed my name to this specification in the presence of 15 two subscribing witnesses.

WILLIAM F. MANGELS.
